UNITED STATES PATENT OFFICE.

RAYMOND O. PFEFFERLE, OF MADELIA, MINNESOTA.

BOX OR RECEPTACLE.

1,395,594.

Specification of Letters Patent. Patented Nov. 1, 1921.

Application filed December 15, 1919. Serial No. 345,098.

To all whom it may concern:

Be it known that I, RAYMOND O. PFEFFERLE, a citizen of the United States, residing at Madelia, in the county of Watonwan 5 and State of Minnesota, have invented certain new and useful Improvements in Boxes or Receptacles, of which the following is a specification.

This invention relates to tin boxes or receptacles, and the primary object of the invention is to provide an improved means for securing a label thereon.

The ordinary tin boxes now in use by druggists for the reception of ointment, 15 salve or the like will not receive a label, *i.e.*, the mucilage on the label will not adhere to the tin and it is therefore an object of the invention to provide an improved means for associating a label with a tin box without 20 necessitating the gluing of the label thereon.

Another object of the invention is to provide an improved box embodying an annular retaining flange or frame carried by the lid of the box for the reception of a label, 25 the box having means for permitting the ready insertion of the label between the flange and the lid.

A further object of the invention is to provide an improved means formed on the 30 lid of a tin box for the reception of a label which is so arranged in relation to the box that the displacement of the label will be eliminated.

A further object of the invention is to 35 provide a tin box having label receiving means formed thereon which is also arranged to carry a transparent protector plate for preventing the soiling of the label and thereby permit the matter printed on 40 the label to be read at all times.

A still further object of the invention is to provide an improved box for the reception of salve, ointment or the like, which is so constructed as to provide a double sealing 45 closure, thereby absolutely preventing the leakage of the material from the box.

A still further object of the invention is to provide an improved box of the above character which is durable and efficient in 50 use, one that is simple and easy to manufacture, and one which can be placed upon the market at a reasonable cost.

Other objects of the invention will appear 55 in the following detailed description taken in connection with the drawings, forming a

part of this specification, and in which drawings:

Figure 1 is a perspective view of the improved box.

Fig. 2 is a central diametric section 60 through the same.

Fig. 3 is a view similar to Fig. 2, showing the box without the transverse protector plate.

Fig. 4 is a horizontal section through the 65 box, and

Fig. 5 is a plan view of the improved box.

Referring to the drawings in detail, wherein similar reference characters designate corresponding parts throughout the several views, the letter A indicates the box 70 having the improved means B for the reception of the label C.

The box A includes a body 10 which as 75 shown is of cylindrical formation and includes the side wall 11 having intermediate its upper and lower edges a laterally projecting rib 12, which forms a seat for the lower edge of the lid or cover, which has associated therewith the label holding 80 means B.

The lid includes a circular imperforate plate 14 having a depending annular flange 15 which is adapted to seat or rest upon the upper edge of the side wall of the box body 85 10, and the meeting point between the annular flange and disk 14 is inclined downwardly and outwardly to provide an inclined guide face 16, the purpose of which will be hereinafter more fully described. 90 The plate 14 and flange 15 have associated therewith the frame 17 which includes the annular side wall 18, which is arranged to be soldered or otherwise secured to the flange 15 and is adapted to extend below the 95 same so as to engage the rib 12. The depending side wall 18 has its upper edge bent inwardly to provide the inwardly extending annular retaining flange 19 which is arranged in spaced relation to the plate 14 100 so as to form a pocket therebetween for the reception of the label C, and the top plate 14 and its flange 15 and the frame 17 forms the means B for holding the label C in position. The cylindrical side wall 18 of the frame 17 is provided adjacent its upper edge 105 with a slot 20 which has a length less than half of the circumference of the box, so as provide a restricted opening to prevent the displacement of the label C from the pocket 110

or space between the frame and plate 14. The slot being of less length than half of the circumference of the lid makes it necessary to slightly bend or spring the label into position, and after the same has been wholly inserted within the slot, the label, owing to its inherent resiliency will resume its normal position. The upper wall of the slot 20 lies in a plane with or below the upper 10 surface of the plate 14 and thus the upper end of the cylindrical side wall 18 forms an abutment for preventing the accidental movement of the label through the slot. In positioning the label in the slot, the inclined surface 16 forms a means for guiding the label between the frame 17 and the top wall 18 and it will be seen that when the label is placed in position the edge of the same will spring up into engagement 15 with the inner surface of the flange 19 and above the slot 20. The label C may be made of paper or any preferred material and when the box is to contain salve, ointment or other oily substance, a transparent flexible plate 21 is provided of circular formation for preventing the label from becoming soiled and unreadable. The transparent plate 21 is interposed between the label C and the frame 17.

30 In Fig. 3 is shown the plate dispensed with and in this form a label of slightly greater thickness than the label shown in Fig. 2 is used or if so desired the frame 17 and the top wall 14 may be arranged slightly closer to each other. The box shown in Fig. 3 is adapted for granular or powdered substance which will not soil the outer face of the box or the label.

From the foregoing description it can be 40 seen that an improved box is provided having means for receiving a label which eliminates the necessity of pasting or gluing the label to the box lid, the box lid being so constructed as to absolutely prevent the displacement of the label or the tearing of the outer edge of the label.

The lid is also constructed so as to provide a double closure for the box so as to prevent the leakage of material between the lid and body of the box, and it will be seen that the lid has a two point contact with the body of

the box, namely where the cylindrical body 18 of the lid engages the rib 12 and where the depending flange 15 engages the upper edge of the body of the box.

55

Changes in details may be made without departing from the spirit or scope of my invention; but,

I claim:

1. The combination with a box cover having a depending flange, a label holding frame having a depending flange arranged to fit about and extend below the flange of the box cover, an inwardly extending flange arranged in superposed relation to the box 65 cover and adapted to project forwardly and overhang the box cover to provide therebetween a compartment for the reception of the label, the flange of said frame having a slot therein of less width than the diameter 70 of said label, whereby the label will have to be sprung into position.

2. A box cover comprising a body plate, a depending flange formed on the periphery of the plate, a label holding frame carried by the depending flange including an annular flange arranged in spaced relation to said body plate to provide therebetween a space for the reception of the label, and a depending flange receiving the flange formed 80 on the body plate and extending below the same, the last mentioned flange having a slot formed therein of less width than the diameter of the label and arranged below the plane of said body plate whereby the 85 accidental displacement of the label through said slot will be prevented.

3. A box cover comprising a top plate, an inclined guide flange formed on the periphery of the top plate, a depending retaining flange carried by the guide flange, an open frame arranged in superposed relation to the top plate and extending beyond the plane of the inclined guide flange, and a depending flange formed on the periphery 95 of the open frame receiving the retaining flange and extending below the lower edge of the frame, the last mentioned flange having a label receiving slot formed therein arranged in a plane below the top plate and 100 leading to said guide flange.

RAYMOND O. PFEFFERLE.
